UNITED STATES PATENT OFFICE.

RICHARD F. GEORGE, OF GLENDALE, CALIFORNIA.

INTERNAL-COMBUSTION ENGINE.

Application filed January 31, 1928. Serial No. 250,749.

My invention relates more particularly to improvements in the valve structure for controlling the intake and exhaust, and has among its salient objects to provide an improved rotary valve turning about the axis of the cylinder, said rotary valve member forming the end wall of the cylinder chamber; to provide an improved cylinder head, with means in connection therewith for operating said rotary valve; to provide improved intake and exhaust ports, whereby quick opening and closing of said ports can be accomplished; and, in general, to provide a simple, practical and efficient form of construction and arrangement in internal combustion engines, whereby a practical and economical rotary valve mechanism is made possible.

In order to fully explain my invention, I have illustrated one practical embodiment thereof on the accompanying sheet of drawings, which I will now describe.

Figure 1 is a top plan view of an engine, showing three cylinders, one shown with the head in place, the middle one shown with the head removed, and the third one (at left) shown with part of the head broken away;

Figure 2 is a vertical, cross sectional view through one cylinder, taken on line 2-2, of Fig. 1; and

Figure 3 is a horizontal sectional view through the cylinder head, removed, and on the line 3-3 of Fig. 2.

Referring now in detail to the drawings, I will describe the embodiment of the invention here shown for illustrative purposes. The cylinder is designated 4, crank case 5, crank shaft 6, crank 7, piston 8, piston rod 9, and water jacket around the cylinder is designated 10.

The cylinder head as shown is composed of the top plate 11, with water jacket 12, and the annular body 13, having the central spark plug chamber 14, with spark plug 15, screwed into the bottom thereof. Said central or annular body 13, has an outer annular chamber 16, and an inner annular chamber 17, indicated in Figs. 2 and 3. The outer annular chamber 16, has four ports 16' therefrom downwardly, designated 16' and shown in Figs. 2 and 3, two only being seen in Fig. 2. The said outer annular chamber also has a port 16^a upwardly connecting with an exhaust pipe 18. The inner annular chamber 17, also has four downward ports, 17', circumferentially spaced from the ports

16', and one upwardly extending port 17^a, connecting with an intake or supply pipe 19. In the side of said central spark plug chamber or well 14, through said body, as seen in Figs. 2 and 3, is a bore 20, with which connects a small oil pipe 21, connected to a supply pipe 22, along the top of the cylinder head.

My rotary valve member, as here embodied, comprises a cup-like member 23, having the central opening 24, for the inner end of the spark plug 15, and having four radially disposed ports, as 25, 25, adapted to be turned to alternately register with the intake ports 16' and the exhaust ports 17', leading from the annular chambers 16 and 17, respectively, in the head body 13. The top surface of this valve member is seen in Fig. 1, in the central cylinder where the head is removed. Said valve member has in said top surface four radial grooves, as 26, with which the inner or lower end of the bore 20 communicates to supply a small amount of lubricating oil from the pipe 21, to the top surface of the bottom of said valve member 23. The annular side member of said valve member is designated 23' and is provided around the outside thereof, between said annular side member and the top of the cylinder, designated 4', with two sealing or piston rings, 27.

Mounted around the top 4' of the cylinder 4, is annular member 28, having teeth 29, around its outer periphery, with its upper portion overlying the upper end of the cylinder top 4', and provided with circumferentially spaced lugs 30, interlocking with the annular side 23' of said valve 23, for turning the same, as hereinafter referred to. An extension 31, on the side of the cylinder 4, houses a worm 32, which meshes with the teeth 29, on member 28, and through said member 28, said rotary valve 23 is revolved. A shaft 33, carries all of said worms 32, as will be understood from Fig. 1. Said worms 32, mesh with the teeth 29, which are really worm gears, as will be understood from the cross sectional view thereof seen in Fig. 2. The shaft 33, is provided with a sprocket wheel 34, as is the crank shaft 6, as at 35, with a sprocket chain 36, connecting the two, within a housing 37, as will be clear from the right hand end of Fig. 1 and Fig. 2.

It is intended that the worms 32, will run in oil in the extensions 31, and that small ports, as 38 and 39, will permit oil to work

through to oil the meeting surfaces between the valve member 23 and the cylinder top 4', on one side, and the outside of the cylinder head or body 13, on the inside of said valve member 23, as will be seen in Fig. 2.

It is intended that the driving connection from the crank shaft 6, through the sprocket chain 36, and the worm and worm gear drive to the valve member will be such 10 that approximately eight revolutions of the crank shaft to one revolution of the valve member 23, will be the ratio of operation.

On the outer surface of the body 13 of the head, at opposite sides, are two vertical 15 grooves, as 13', to convey lubricant from the small port 39, Fig. 2, to the joint between said body 13 and the side of the valve member 23.

The use and operation of the invention 20 may be briefly described as follows:

Referring to Fig. 2 and also to Fig. 3, it will be seen that the piston 8 is starting upwardly on an exhaust stroke; that valve ports 25, in the rotary valve member 23, are 25 in register with ports 16' in said head, and with the exhaust pipe 18, as will be clear from Fig. 2. At the finish of the exhaust stroke of said piston, said valve member is turned to bring its ports 25 into register 30 with the intake ports 17', so that the down stroke of said piston takes in the charge of explosive mixture from intake pipe 19. It will be noted that the ports 17' are only a short distance from the exhaust ports 16'. 35 The distance between ports 17' and the next exhaust port 16', moving in a direction contra-clockwise, is greater and the compression stroke and the power stroke takes place before said rotary valve ports 25 turn to 40 again register with the exhaust ports 16'. It will thus be seen that the power or expansion in the cylinder 4 is against the rotary valve member 23, forcing it uniformly against the head 13, with each explosion and 45 each compression. It will also be seen that there is the exhaust, when ports 25 register with ports 16', intake as said ports 25 move to 17', compression during the continued movement of ports 25 from 17' toward the 50 next 16', also the power or explosion, and then the exhaust as said ports 25 come again into register with the next exhaust port 16', making a four cycle engine, and completing 55 each cycle with each quarter turn of the rotary valve member 23.

While I have shown and described one practical embodiment of my invention on the accompanying sheet of drawings, I am aware that changes in the details of construction and arrangement can be made 60 without departing from the spirit of the invention, and I do not, therefore, limit the invention to the specific showing made for descriptive purposes, except as I may be 65 limited by the hereto appended claims.

I claim:

1. In an internal combustion engine, in combination with a cylinder, a rotary valve member of cup-like form with ports through its bottom, and forming the end wall of said cylinder, a cylinder head fitting over said cylinder with a body portion fitting down into said cup-like valve member, inlet and exhaust ports through said head and said body portion and adapted to register with the ports through said valve member as said valve member is rotated, and means driven from the crank shaft of said engine for rotating said valve member. 75

2. In an internal combustion engine, in combination with a cylinder, a rotary valve member of cup-like form set into the open end of said cylinder with ports through its bottom, a cylinder head fitting over said valve member with a body portion fitting down into said valve member, said body portion having annular chambers concentric with each other and forming intake and exhaust chambers with ports therefrom to register with the ports in said valve member as the latter is rotated about the axis of said cylinder, intake and exhaust pipes connected through said head to said annular chambers, a central well formed in said head with a central opening through the valve member, a spark plug seated therein, means for revolving said valve member about the axis of said cylinder, and means for lubricating the joints between said valve member and the cylinder wall and the body portion of the cylinder head. 90 95

3. In an internal combustion engine, a cylinder, a cylinder head having a body portion provided with concentric annular chambers formed therein, with ports leading therefrom inwardly, a rotary valve member fitted into said cylinder against the bottom of the body portion of said head and having ports therethrough adapted to be turned into and out of register with the ports from said body portion, means connecting intake and exhaust pipes to said head and said annular chambers, and means for rotating said valve-member. 105 110

4. In an internal combustion engine, a cylinder enlarged at one end as to internal diameter, a rotary valve member of cup-like form rotatably seated in said enlarged end and having ports through its bottom to serve as intake and exhaust ports, a cylinder head fitted over said valve member with a body portion seated down in said cup-like form and having intake and exhaust chambers formed therein with ports through its bottom to be put into register with the ports in said valve member as the latter is revolved, intake and exhaust pipes connected through said head to said chambers, a spark plug seated through said head and said valve member, centrally thereof, and means 115 120 125 130

for driving said valve member, whereby it revolves between said cylinder and said interfitting body portion.

5. In an internal combustion engine, a cylinder enlarged at one end to increase its internal diameter, a rotary valve member of cup-like form seated in said enlarged end and having ports through its bottom and having a central opening, a cylinder head 10 fitted over the end of said cylinder and said valve and having a body portion fitting down in to the cup-like form of said valve, said head having concentric, annular chambers formed therein for intake and exhaust 15 chambers, with ports opening through the bottom thereof in position to register with the valve ports as the latter is revolved, means for revolving said valve member about the axis of said cylinder, a spark plug 20 inserted through said head and through the central opening of said valve member, and means for lubricating said revolving valve member between the cylinder wall and the outside of said body portion of said head, 25 substantially as described.

6. In combination, a cylinder having one end enlarged in diameter to form an offset portion, a rotary valve member seated in said enlarged portion and having

radially disposed ports through said valve member into said cylinder, a cylinder head fitted over the end of said cylinder and said valve member, said head having intake and exhaust chambers formed therein with ports opening therefrom through the inside thereof to register with the ports through said valve member as the latter is revolved, means for revolving said valve member between said cylinder and said head, intake and exhaust pipes connected through said head with said intake and exhaust cylinders, and ignition means centrally of said head and said rotary valve member.

7. In an internal combustion engine, a cylinder, a rotary valve member closing the open end of said cylinder and having radially disposed ports through its body into said cylinder, a fixed cylinder head secured to said cylinder and interfitting with said valve, said head having intake and exhaust 50 chambers with ports therefrom to register with said valve ports when the latter is revolved, and means for revolving said valve member.

Signed at Los Angeles, Los Angeles 55 County, California, this 26 day of January, 1928.

RICHARD F. GEORGE.
